(57) **CLAIM**

The ornamental design for aroma diffuser set, substantially as shown and described.

DESCRIPTION

FIG. 1 is a front perspective view of an aroma diffuser set shown fully assembled; The body of the aroma diffuser and the essential oil bottle are shown separately for convenience of illustration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a perspective view of showing the aroma diffuser shown in a separated state;

FIG. 10 is a front perspective view of the essential oil bottle;

FIG. 11 is a rear perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The broken lines in the drawings illustrate the portions of the aroma diffuser set, which form no part of the claimed design.
